Primary Examiner — Patricia A Palasik

CLAIM

The ornamental design for a press frame with integrated hydraulic ram and return springs, as shown.

DESCRIPTION

FIG. 1 is an upper front right perspective view of a press frame with integrated hydraulic ram and return springs showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an upper front left perspective view thereof.

1 Claim, 8 Drawing Sheets
